(57) **CLAIM**

The ornamental design for an air freshener device, as shown and described.

DESCRIPTION

FIG. 1 is a front top perspective view of a first embodiment of an air freshener device that includes a base unit and a fragrance cartridge, wherein the fragrance cartridge is removed from the base unit for clarity of illustration;

FIG. 2 is a rear top perspective view of the fragrance cartridge of FIG. 1;

FIG. 3 is a top plan view of the fragrance cartridge of FIG. 1;

FIG. 4 is a left side elevation view of the fragrance cartridge of FIG. 1, the right side elevation view being identical thereto;

FIG. 5 is a front elevation view of the fragrance cartridge of FIG. 1;

FIG. 6 is a rear elevation view of the fragrance cartridge of FIG. 1;
FIG. 7 is a bottom plan view of the fragrance cartridge of FIG. 1;
FIG. 8 is a front top perspective view of a second embodiment of an air freshener device that includes a base unit and a fragrance cartridge, wherein the fragrance cartridge is removed from the base unit for clarity of illustration;
FIG. 9 is a top plan view of the fragrance cartridge of FIG. 8;
FIG. 10 is a left side elevation view of the fragrance cartridge of FIG. 8, the right side elevation view being identical thereto;
FIG. 11 is a front elevation view of the fragrance cartridge of FIG. 8;
FIG. 12 is a rear elevation view of the fragrance cartridge of FIG. 8;
FIG. 13 is a bottom plan view of the fragrance cartridge of FIG. 8;
FIG. 14 is a front top perspective view of a third embodiment of an air freshener device that includes a base unit and a

fragrance cartridge, wherein the fragrance cartridge is removed from the base unit for clarity of illustration;
FIG. 15 is rear top perspective view of the fragrance cartridge of FIG. 14;
FIG. 16 is a top plan view of the fragrance cartridge of FIG. 14;
FIG. 17 is a left side elevation view of the fragrance cartridge of FIG. 14, the right side elevation view being identical thereto;
FIG. 18 is a front elevation view of the fragrance cartridge of FIG. 14;
FIG. 19 is a bottom plan view of the fragrance cartridge of FIG. 14; and,
FIG. 20 is a rear elevation view of the fragrance cartridge of FIG. 14.
The broken lines in the figures illustrate unclaimed portions of the air freshener device.
